CLAIM

The ornamental design for a needle valve for carburetors, as shown and described.

DESCRIPTION

FIG. 1 is a top, plan view of the needle valve for carburetors, showing the new design, wherein the bottom plan view is identical to FIG. 1;

FIG. 2 is a front, end elevation view of the needle valve for carburetors from FIG. 1;

FIG. 3 is a rear, end elevation view of the needle valve for carburetors from FIG. 1;

FIG. 4 is a right side, plan view of the needle valve for carburetors from FIG. 1, wherein the other side plan view is identical to FIG. 4;

FIG. 5 is a perspective view of the needle valve for carburetors from FIG. 1; and,

FIG. 6 is an exploded assembly perspective view thereof, showing the new design in a state of use with a carburetor and a tool.

The broken lines in the drawings show unclaimed portions of the needle valve for carburetors and form no part of the claimed design.
